[57] CLAIM

The ornamental design for an auxiliary automotive
brake light, as shown and described.

DESCRIPTION

FIG. 1 is a front elevational view of the auxiliary automobile
brake light showing my new design;

FIG. 2 is a side elevational view thereof, the opposite
side being a mirror image thereof;

FIG. 3 is a top plan view thereof;

FIG. 4 is a rear elevational view thereof; and

FIG. 5 is a bottom plan view thereof.

FIG. 1

FIG. 4

FIG.2

FIG.3
